UNITED STATES PATENT OFFICE.

LOREN FANCHER, OF DETROIT, MICHIGAN.

DEVICE FOR FORCIBLY OPENING DOORS.

SPECIFICATION forming part of Letters Patent No. 233,665, dated October 26, 1880.

Application filed September 16, 1880. (No model.)

To all whom it may concern:

Be it known that I, LOREN FANCHER, of Detroit, Wayne county, Michigan, have invented an Improvement in Door-Openers, of 5 which the following is a specification.

The nature of this invention relates to certain new and useful improvements in devices designed for use by firemen in forcibly opening doors in cases of fire; and the invention consists in the peculiar construction and operation of the parts, all as more fully hereinafter set forth.

Figure 1 represents my improved device as adjusted to a door. Fig. 2 is a side elevation, 15 partially in section. Fig. 3 is a plan view.

In the accompanying drawings, which form a part of this specification, A represents the main bar or lever of the device, provided at one end with a curved serrated foot, *a*. Near 20 this end of the lever A is formed a stud, *b*, to which is pivotally secured one end of the lever B. This lever is hollow the greater portion of its length, and has formed in it a longitudinal notched slot, *c*.

C is a rod, which slides easily within the lever or part B, and is provided with a pin, *d*, which engages with one of the notches in the slot *c*, as may be desired. Upon the outer end of the rod C is pivotally secured the spurred 25 swivel-plate D.

In operation, the lever A is placed upon the floor or walk before the door which it is desired to force open, and the parts B C are turned up and adjusted so that the plate D 30 will rest against the door under the knob or latch. By then raising up the outer end of

the lever A, the foot *a* is compelled to engage with the floor or walk, and continued upward movement of the lever will force the door open.

It has been found by the use of this device 40 that doors can be easily and quickly forced open without damaging the door beyond the slight indentations made by the spurred plate and without danger of breaking the glass, which, in many doors, is very costly, while the 45 use of "rams" in cases of fire, being brought against the door with a sudden jar, will almost invariably break the glass, and often causes serious injury to the firemen.

I do not desire to confine myself to the exact manner of procuring the adjustment of the parts B C, as there are various ways in which such adjustment could be obtained without departing from the spirit of my invention.

What I claim as my invention is—

1. A device for opening doors, consisting of the levers A B, constructed, arranged, and operating substantially in the manner and for the purposes described.

2. In a device for opening doors, the combination of the levers A B with the adjustable rod C, substantially as and for the purposes set forth.

3. In a device for opening doors, the combination of the lever A, provided with the serrated foot *a* and lever B, with the adjustable rod C and spurred plate D, substantially as and for the purposes specified.

LOREN FANCHER.
